UNITED STATES PATENT OFFICE

2,450,927

BOTTLE HOLDER

Paul E. Allen, Skokie, Ill., assignor to Baby's Pal Company, Chicago, Ill., a corporation of Illinois

Application October 11, 1944, Serial No. 558,133

2 Claims. (Cl. 248—104)

1

The present invention relates to bottle holders and especially to a novel device for receiving and retaining a nursing bottle in proper position for nursing an infant.

Among the objects of the present invention is to provide a nursing bottle holder of the type adapted to retain the bottle in any desired position during the feeding period. To permit such ready adjustment, the base is preferably provided with a loose mass of relatively small and heavy mobile particles, which although freely shiftable, when placed in the proper position for feeding, retains the bottle in that position.

Another important object of the present invention is to provide a nursing bottle holder formed of two parts, a covering or outer member and a removable bag or inner member adapted to contain the mass of relatively heavy mobile particles. By making the inner bag readily removable, the outer member may be quickly and easily washed and maintained sanitary.

Another important advantage of the present invention is to provide a bottle holder of simplified and cheap construction and one requiring a minimum of effort to keep clean and sterile.

The invention further resides in the construction, combination and arrangement of parts illustrated in the accompanying drawings, and while there is shown therein a preferred embodiment, it is to be understood that the same is susceptible of modification and change, and comprehends other details, arrangements of parts, features and constructions without departing from the spirit of the invention.

In the drawings:

Figure 1 is a perspective view of the novel bottle holder with a conventional style of bottle mounted therein.

Figure 2 is a view, part in vertical cross section and part in side or end elevation through the bottle holder and bottle, with the section taken on the line 2—2 of Figure 1.

Figure 3 is a fragmentary enlarged view in perspective showing the contractile band or means for tightly encompassing and retaining a bottle in position.

Referring more particularly to the disclosure in the drawings, the novel illustrative embodiment there shown comprises a bottle holder 1 of any suitable fabric or cloth which may be readily washed or sterilized as required. Mounted upon the upper surface of the bottle holder is a nursing bottle 2 of any desired construction or contour which is adapted to be mounted within the confines of the band 3 and retained therein dur-

ing nursing. This band is preferably provided with elastic whereby it will closely conform to and tightly grip the bottle. It further has the advantage of maintaining the temperature of the bottle and its contents for a considerable period of time.

The bottle holder is formed to provide a bag-like base 4 consisting of cloth or fabric sections sewn or otherwise joined together and with a lower edge 5 thereof open for substantially its entire length but normally closed by a slide fastener, buttons or other closure 6. Within this base is removably mounted a bag 7 containing a filler giving stability to the holder. This filler may be any suitable mass that is readily shiftable, but preferably I employ a loose mass of relatively heavy mobile particles which mass may be readily shifted to maintain the holder and bottle in any desired adjusted position. In practice I have found that particles such as rice, beans, gravel or other available particles having a sufficient weight and mobility give excellent results and the bag and base will be readily adapted to the surface contour of any support upon which it may be placed.

The bottle holder presents no projections or sharp corners upon which the infant may be injured and as the bag 7 may be readily removed by opening the closure to the base or covering, the latter including the flexible band may quickly and easily be washed and maintained sterile.

Having thus disclosed my invention, I claim:

1. A bottle holder for nursing bottles comprising an outer bag and an inner bag fitting conformably within and completely enclosed by but readily removable from or replaceable in the outer bag, the inner bag being provided with a filler consisting of a shiftable and loose mass of relatively heavy mobile particles adapted to conform to a surface on which it is placed for retaining the holder and bottle in any desired position for nursing an infant, the outer bag being formed of a washable fabric providing a protective covering for the inner bag, a closure provided along one edge of the outer bag for quick insertion or replacement of the inner bag with its filler, and an elastic band on and forming an integral part of the upper surface of the outer bag for receiving and retaining a nursing bottle thereon.

2. A bottle holder for nursing bottles consisting of an integral outer bag provided with a flexible band on its upper surface for receiving and retaining a nursing bottle and formed of a washable fabric, a removable inner bag adapted to fit

conformably within and completely enclosed and protected by the outer bag and provided with a mass of loose and relatively heavy mobile particles adapted to readily shift and conform to the surface on which the holder is placed for retaining a nursing bottle in a desired position for nursing, and a closure in the outer bag for securing quick access to the inner bag for ready removal or replacement thereof.
